UNITED STATES PATENT OFFICE.

HAROLD O. WOOLLEY, OF MAPLEWOOD, NEW JERSEY, ASSIGNOR TO POWER SPECIALTY COMPANY, OF NEW YORK, N. Y., A CORPORATION OF NEW YORK.

COMBINED SUPERHEATER AND BOILER.

Application filed October 25, 1922. Serial No. 596,700.

This invention relates to a combined boiler and superheater and is directed to the provision of a construction which will provide for the maximum of efficiency of gas flow in both the boiler and superheater. A further object of the invention resides in the provision of an improved arrangement of superheater and boiler which may be readily applied to boilers already in use without extensive change or alteration. Other objects and advantages will be set forth in further detail in the accompanying specification and drawings which show a preferred embodiment of the invention.

15 The boiler comprises a lower water drum 10, an intermediate drum 11 and an upper steam drum 12. Connecting the drums 10 and 11 there is a bank of substantially horizontal boiler tubes 13. A second bank of 20 vertical boiler tubes 14 connect drums 11 and 12 and a third bank of inclined tubes 15 connect the steam and water drums 12 and 10. 25 16 is the fire chamber containing the usual grate bars not shown; and 17 is the duct to the stack.

The superheater is preferably located in a housing 18 in front of the boiler and alongside of the bank 14. When applying superheaters to boilers already in use the front wall of the boiler is removed and the housing 18 substituted therefor. The superheater comprises inlet and outlet headers 19 and 20 which extend from one end of the housing to the other and into which are connected 30 U shaped superheater elements 21. A suitable supply pipe 22 leads from the steam drum 12 to the inlet header 19. By the above construction the entire weight of the superheater elements is carried directly upon 35 the headers. Preferably the headers are located back of the drum 11 so as to be protected thereby from the direct access of hot gases from the fire.

To direct the hot gases over the boiler and superheater tubes in the most efficient manner baffles 23, 24, 25 and 26 are provided. These baffles serve to direct the hot gases of combustion longitudinally and transversely over the tubes 13 thence transversely over the lower ends of the bank of tubes 14 into the superheater chamber and at right over the corrugated elements thereof. From the superheater the gases pass over the top of

the baffles 25 and transversely across the upper parts of bank 14, and thence downwardly 55 along the tubes 15 over baffle 26 to the outlet duct 17.

By directing the gases in this manner, they are caused to flow at high velocity over both the boiler and superheater tubes. Furthermore, the gases passing over the superheater are tempered to a considerable extent before reaching the superheater by reason of having previously passed over and imparted heat to both banks of boiler tubes 13 and 14. 60 This tempering of the gases prevents over heating of the superheater elements and at the same time the heat of the hot gases is efficiently imparted to the water traversing 65 the boiler tubes.

What I claim is:

1. A combined boiler and superheater, comprising in combination, an upper steam drum, a pair of lower water drums, banks of boiler tubes connecting the said drums, and including a horizontal, a vertical and an inclined bank of tubes, a superheater having vertically arranged tubes disposed at one side of the vertical bank of tubes in a superheater chamber disposed above and to the 75 side of the lower water drum connected to the vertical bank of tubes, and baffles arranged intermediate the boiler tubes and having connected therewith a horizontally extending baffle extending through the vertical bank of boiler tubes to a point adjacent the superheater, said baffles being adapted to direct all of the hot gases of combustion first over the horizontal and thence laterally over the vertical tubes and thence 80 transversely across the tubes of the superheater whereby all of the gases are tempered in temperature before reaching the 85 said superheater.

2. A combined boiler and superheater 95 comprising a boiler having an upper steam drum, an intermediate drum, a lower water drum, a bank of inclined boiler tubes connecting the upper and lower drums, a bank of vertical boiler tubes connecting the intermediate and upper drum and a third bank of boiler tubes connecting the intermediate and lower drums, a superheater having vertically arranged tubes disposed adjacent the vertical bank of boiler tubes, inlet and outlet headers for said superheater disposed be-

low and behind the intermediate drum, and said intermediate drum being adapted to baffles disposed between the banks of boiler tubes having portions thereof extending through the vertical bank of boiler tubes, said baffles being adapted to direct the hot gases over various boiler tubes and transversely over the tubes of the superheater, shield the superheater headers from the direct access of hot gases. In testimony whereof I hereto affix my signature.

HAROLD O. WOOLLEY.
